UNITED STATES PATENT OFFICE

JOSEPH A. SHKAIR, OF BROOKLYN, NEW YORK

DESIGN FOR A TEXTILE FABRIC USED FOR BEACH COATS OR SIMILAR GARMENTS

Application filed November 18, 1929. Serial No. 33,483. Term of patent 7 years.

To all whom it may concern:

Be it known that I, JOSEPH A. SHKAIR, a citizen of Syria, residing at the borough of Brooklyn, New York city, in the county of Kings and State of New York, have invented a new, original, and ornamental Design for a Textile Fabric Used for Beach Coats or Similar Garments, of which the following is a specification, reference being had to the accompanying drawing, forming part thereof.

The figure is a face view of a textile fabric used for beach coats or similar garments, showing my new design.

I claim:

The ornamental design for a textile fabric used for beach coats or similar garments, as shown.

In testimony whereof I have affixed my signature.

JOSEPH A. SHKAIR.
